UNITED STATES PATENT OFFICE.

GEORGE H. F. SCHRADER, OF NEW YORK, N. Y.

TIRE-VALVE CAP.

SPECIFICATION forming part of Letters Patent No. 691,296, dated January 14, 1902.

Application filed April 15, 1899. Serial No. 713,097. (No model.)

To all whom it may concern:

Be it known that I, GEORGE H. F. SCHRADER, a citizen of the United States, residing in the city, county, and State of New York, have invented certain new and useful Improvements in Tire-Valve Caps and the Like, of which the following is a specification.

This invention relates to caps for tire and other valves and is especially adapted to the caps of bicycle-valves.

Heretofore it has been common to construct bicycle valve-caps with a screw-driver tip projecting from the top of the cap, and according to an improved cap invented by me the projecting tip has been formed with a diametrical recess in its end and a socket opening at the tip end. In use it is found that the screw-driver tip on the cap will strike and tear the wearing-apparel of the user of a bicycle provided with tip-caps, and with the notched or socketed caps it has been found that dirt may enter the notch and interfere with the use of the tip of the cap as a tool.

My present invention aims to avoid both the danger of injury from the use of the projecting-tip valve-caps and the danger of entrance of dirt into the notch or socket in the tip when a tip having these features is employed.

To this end in carrying out my present invention I provide a protector for the end of the tip of a bicycle valve-cap adapted to cover or guard the end thereof in such manner that the tip will be incapable of injuring anything it strikes and adapted to exclude the entrance of foreign matter into a socket or notch in the tip. This protector is movable and preferably removable and may be in the form of an elastic cap of soft material, being preferably made to spring on the end of the tip and envelop this end at all points or corners thereof and closing any notches or socket which may exist at the end of the tip. I prefer to construct the cap as a hollow cup-shaped pure-rubber body.

My invention also provides an improved shape or construction of the cap itself, consisting in forming the cap with an annular conical wall between the end of the tip and the body of the cap, which wall diverges from the cylindrical end of the tip toward the body

in the form of a frustum of a cone and serves when the cap is inverted and inserted in the socket of the valve to engage the walls of the socket and guide the tip into concentric relation with the socket.

The invention also provides other details of improvement in the construction of a tubular valve-cap, all of which will be fully herein-after set forth.

In the accompanying drawings, Figure 1 is a side elevation of a tire-valve, showing the preferred form of my improved cap. Fig. 2 is a similar view showing the cap in axial section. Fig. 3 is a side elevation of the valve and cap, the valve-shell being partly broken away and the cap being shown as inverted and inserted in the socket of the shell. Fig. 4 is a plan, axial, and bottom plan of the new protecting-cap alone; and Fig. 5 is a plan view of the improved valve-cap alone.

Referring to the drawings, let A designate a tire-valve shell, B the socket therein, and C the cap therefor. The shell A may be any suitable valve-shell. That shown has an external screw-thread *a*, engaged by an internal screw-thread *b* in the open lower end of the cap C, this cap screwing over the end of the shell when in the closed position. The shell has an internal screw-thread *c* in its socket B, in which socket is screwed a plug D, having a screw-driver projection *d*. The cap shown is of an improved construction invented by me, in which the cap instead of having a screw-driver point at its outer end has a screw-driver notch E, crossing the end of its tip F, has a socket G opening at the end of this tip, is tubular from end to end, and has an internal cup-shaped disk H, and a similarly-formed internal packing-washer I. The washer I is pressed on the end of the shell when the cap C is applied thereto, independent rotation of the cap relatively to the washer being permitted by the antifriction-disk H. When the cap is removed, it can be inverted and its tip F inserted into the socket B until its notch E engages the projection *d* of the plug D, whereby the cap can be used to screw out or in the plug. None of the features as thus far described constitute any part of my present invention and any suitable construction may be substituted instead of the con-

struction shown, which latter is taken as a convenient example for illustrating the preferred form of my present improvements.

According to the preferred form of that 5 feature of my present invention which provides a protective cap for the cap C, I provide a cap J of soft elastic india-rubber adapted to be sprung over and embrace the end of the tip. The cap shown is of cup shape, having a 10 socket e, formed to receive and fit the end of the tip, substantially cylindrical side walls f, and the rounded and imperforate top wall g. When contracted, it is of slightly smaller internal diameter than the external diameter of 15 the tip. Its lower edges are thinned to facilitate expansion of the open end of its socket sufficiently to easily pass the cap over the tip, and its top wall is thickened to increase the compression exerted by the cap on the tip as 20 the cap is pushed home on the cylindrical wall h of the tip. The caps J may be made and sold as separate articles of manufacture or they may be applied to the valve-caps and sold therewith.

25 In use a cap J is sprung over a tip and kept thereon until the tip is to be inverted for use as a tool, in which case the cap is pulled off and is again restored to the tip after use of the latter as a tool ceases. The cap is sufficiently smooth and soft to avoid all danger of 30 injury to anything which it may strike or come in contact with and provides a hermetic closure for the open end of the tip, absolutely guarding against ingress of dust or moisture.

35 It is so inexpensive that it can be easily replaced if lost or worn out.

According to another feature of improvement I construct the cap C with a conical exterior wall K, between the cylindrical end h 40 of the tip and the top wall i of the body of the cap. This wall is in the form of a truncated cone and serves to guide and center the end of the tip in the socket B when the cap is inverted.

45 According to another feature of improvement I construct the cap C as a tubular cap having an inturned end j at each side of the notch E, so that these ends constitute two parallel flat bearing-surfaces in the shape of

segments of a circle and in planes at right 50 angles to the axis of the cap located at each side of the notch E, of which their adjacent walls constitute the sides, as best seen in Fig. 5. Thus the interior of the end of the tip is cylindrical up to its extremity, where its cylindrical walls are terminated by bending in 55 the walls to form the end L, through which end walls the notch E passes, the bottom walls k of this notch being in the shape of arcs of 60 circles and separated to form the intervening socket G, which traverses the tip. This construction gives strength and great utility, improves the appearance of the end of the tip, and cheapens the cost of manufacture of the 65 cap.

In use a cap of this construction will be employed as the ordinary cap of this kind.

It will be seen that my invention provides improvements in tire-valves which can be readily and advantageously availed of, and 70 it will be understood that I do not limit myself to the particular details of construction, arrangement, or combination of features set forth as constituting the preferred form of my present invention, since my present improvements can be employed in whole or in part according to such details of construction, 75 arrangement, and combination of features as the circumstances or the judgment of those skilled in the art may dictate without departing from the spirit of my invention.

What I claim is—

In tire-valve caps, a cap having a body and a projecting tip of smaller diameter than said body and adapted to be inserted into the 85 socket of a valve-shell, and having between said tip and body a tapering outer wall K, diverging from said tip toward said body and constituting a guiding-surface for centering said tip during its insertion into a socket. 90

In witness whereof I have hereunto signed my name in the presence of two subscribing witnesses.

GEORGE H. F. SCHRADER.
